SEPARATOR OR CLASSIFIER FOR ORE PULP AND THE LIKE

Filed Jan. 23, 1932

UNITED STATES PATENT OFFICE

1,969,619

SEPARATOR OR CLASSIFIER FOR ORE PULP
AND THE LIKEDonald MacLean, Brakpan, Transvaal, Union of
South AfricaApplication January 23, 1932, Serial No. 588,349
In Union of South Africa November 23, 1931.

1 Claim. (Cl. 209—465)

This invention relates to separators or classifiers applicable for use in the treatment of ore pulp and other similar mixtures of solids and liquids.

5 More particularly the invention appertains to classifiers of the mechanical type adapted for the treatment of an unclassified pulp or mixture of ore particles in water or other liquid.

Although more especially designed for the treatment of ore pulp and other similar mixtures of solids and liquids, the separator or classifier can also be used for the separation or classification of any granular material which has been mixed with water or other liquid, in order to 10 separate the solid material, or any desired portion thereof, in a practically dry condition, out of the mixture.

The object of the invention is to design an efficient classifier or separator capable of expeditiously treating or dealing with a large volume of the mixture or pulp, and one in which the separated coarser product can be obtained in a substantially dry state.

According to the invention the classifier or separator includes a stationary tank or vessel provided with a conical bottom which is upwardly inclined in the direction of the centre of the tank or vessel. The cone forming the conical bottom is short or shallow, and the truncated upper end thereof provides a central opening or outlet for the separated or classified coarser product.

Means are provided for introducing the ore pulp or mixture near the wall of the tank or vessel on the inside, and in a preferably substantially tangential direction, and the tank or vessel is constructed to provide a discharge opening for the water or other liquid and associated finer component of the mixture, which outlet is placed at the rear of the inlet relative to the direction of the swirling movement of the mixture in the tank or vessel.

Means are provided which operate to discharge the coarser solid component through the central discharge opening. These means may be of such a construction that they will impart or aid the swirling motion of the mixture inside the tank or vessel and may be in the form of a 45 rotating spiral blade device extending from a point near the wall of the tank or vessel to a point at one side of or above the discharge outlet.

The invention will be described in detail, with 55 the aid of the accompanying sheet of drawing

wherein a practical embodiment of the same is illustrated.

In the drawing.

Fig. 1 is a central sectional elevation of the classifier or separator, 60

Fig. 2 is a plan thereof, and

Fig. 3 is a sectional elevation through the one side of the vessel, looking in the direction of the tangential inlet for the pulp or mixture, the plane of section being indicated by the dotted line x—x in Fig. 2. 65

The tank or vessel which, as shown, is preferably cylindrical, includes the metal casing 1, which forms the vertical wall thereof, and the conical bottom 2. The upper edge of the tank 70 or vessel is shown strengthened by an angle iron ring 3, and the conical bottom 2 is flanged and secured to the casing 1 by means of the angle iron ring 4. 5 is a stiffening angle iron ring arranged within and secured to the underside of the conical bottom 2, and 6, 7, are rests for the tank or vessel. 75

The bottom 2 is provided on the inside of the tank or vessel with a lining 8 of concrete or other material of suitable thickness. As shown more 80 particularly in Fig. 1, the conical bottom 2, 8, is truncated at its upper end and provides a large central vertical passage or outlet 9; 10 being a discharge pipe, secured to the tank bottom 2 by ring or flange 11, below the opening 9, for the 85 separated or classified coarser product which passes through said outlet 9. As seen more particularly in Fig. 1 the conical bottom 2 and its lining 8 are in the form of a short or shallow cone which is upwardly inclined from the bottom edge of the casing 1 in the direction of the centre of the tank or vessel. 90

In the wall 1 of the tank or vessel and near its upper edge there is provided the inlet for the pulp or mixture to be treated. The inlet is 95 shown fitted with an elbow piece 12 for delivering the inflowing stream of pulp to the tank substantially tangentially to the wall of the same. 13 is a box or receptacle for receiving the pulp or mixture, from which box 13 the pulp 100 flows to the tank or vessel through the elbow piece 12, and 14 represents, in dotted lines, a launder or trough for leading the mixture or pulp into the box or receptacle 13. 105

In the wall or side 1 of the tank or vessel, at some distance to the rear of the inlet pipe 12 relative to the direction of the inlet flow indicated by the arrow in Fig. 2 there is provided an outlet or discharge opening 15 for the separated or classified fine or undersize product. 110

and the bulk of the water or solution. The discharge outlet 15, as shown, is adjustable as to height or level of the discharge lip 16. For this purpose a portion of the side 1 of the tank 5 may be cut away to a suitable depth, and constructed with guideways 17 to receive removable slats 18 to adjust the height of the discharge level or lip 16, over which the mixture flows into a suitable launder or trough 19 by means 10 of which it may be conducted to any desired point. The launder 19 is shown constructed of some considerable depth so as to receive the overflow over the lip 16 or through the opening 15 at any height or level within the range of 15 adjustment of the lip 16.

In the embodiment of the invention illustrated rotating means are provided inside the tank or vessel for discharging the coarser separated component of the mixture through the 20 discharge outlet opening 9, and aiding to impart the swirling or circular motion to the pulp, these means are shown in the form of a spiral rake device or scraper blade 20, one end 21 of which extends to within a short distance of the 25 wall 1 of the tank and the other to a point 22 above one side of the central outlet opening 9 in the conical bottom 2. The lower edge of the spiral rake or scraper 20 conforms to the shape of the conical bottom 2 of the tank, and projects to within a short distance of the same— 30 see Fig. 1.

23 is a suspended driving shaft for imparting a horizontal rotary motion to the rake or scraper 20, on the lower end of which shaft 23 is fixed a boss 23a to which is attached a plurality of downwardly inclined radial arms 24, to which the spiral rake or scraper blade 20 is rigidly attached by means of brackets 25.

In the inner convolutions of the spiral rake 40 or blade 20 there is shown provided a number of holes 26 in spiral formation. These holes will allow any of the water or liquid and fine solid component of the pulp in suspension therein to flow from the inner in the direction of the outer 45 coils of the spiral rake or scraper.

The means whereby the shaft 23 is suspended centrally above the tank or vessel includes three parallel beams or girders 27, 28, 29, two angle iron frames 30, 31, fixed to the girders 28, 29, 50 respectively, and a transverse plate 32 carried by the said frames 30, 31. On the plate 32 is arranged a ball bearing 33 by which the vertical driving shaft 23 is suspended; 34, 35, being steady bearings for the shaft 23 carried by plates 36, 37, respectively, fixed to the beams or girders 28, 29. The plate 36 acts as a splash plate and prevents the pulp being splashed on to the worm drive. 38 is a worm wheel fixed on the shaft 23, which worm wheel runs in an oil 60 bath in a casing 39; 40 being the cover plate for the casing 39, and 41 a cover or casing for the ball bearing. 42 is an eye-piece fixed to the upper end of the shaft 23 and enclosed by the casing 41, which ring or eye-piece 42 can be 65 used for lifting the shaft 23 and the attached spiral rake or scraper device, if and when desired. 43 is the worm shaft which is carried in a bearing 44 on the girders 27, 28, and bearings 45, 46, provided in opposite sides of the casing 39. 70 On the shaft 43, in the casing 39, between bear-

ings 45, 46, is provided the worm 47 which engages with and drives the worm-wheel 38, which in turn imparts the rotary motion to the shaft 23 and through it to the rake or scraper blade 20. 48 is a driving pulley on the shaft 43 and 49 a shaft coupling. 50 is a thrust bearing for the shaft 43 inside the casing 39.

On the top of the radial arms 24, in proximity to their outer ends, there is secured by hook-shaped bolts 52 a downwardly and outwardly inclined annular plate or shield 51 which operates to distribute the pulp around the interior wall 1 of the tank. This plate 51 is provided around its upper edge with a vertical splash flange 53.

In the operation of this embodiment of the invention, the pulp or mixture to be treated flows in a tangential direction from the inlet elbow piece 12 down between the rim or periphery of the distribution plate or shield 51 and the wall 1 of the tank or vessel, into the space in the latter in which the spiral rake device or scraper 20 operates. Under the action or influence of the rotary motion of the spiral rake or scraper 20 and the tangential inflow of the 100 pulp, the heavier or coarser particles of the mixture are caused to move up the inclined bottom 2 towards the central outlet orifice 8 in the top thereof, whence they pass through the outlet or discharge pipe 10, while the water or solution and the fine or undersize product pass out of the tank or vessel over the discharge lip 16, the height or level of which will have been adjusted to effect the desired result, according to 105 the nature of the pulp or mixture to be treated and the size of the particles of the product to be separated.

The forces which are set up or developed due to the rotation of the spiral rake or scraper device 20 at a suitable rate of speed, ensure a 110 clean or high degree of separation of the fine particles and liquid from the dry coarse product. Any requisite or desired adjustment can be effected by varying the speed of rotation of the spiral rake or scraper 20 and/or by raising or 115 lowering the level or height of the overflow lip 16.

What I claim as my invention and desire to protect by Letters Patent is:—

A separator or classifier for ore pulp and the like, including a stationary vessel for receiving the pulp to be treated, said vessel having a right conical bottom in the form of an upright truncated shallow cone, the angle of which is less than the angle of repose of the solid material which is deposited thereon, which cone is constructed at its upper truncated end to provide a central discharge outlet for the coarser separated product, said vessel also having a peripheral outlet for the finer product and liquid, 125 means for introducing into the vessel near the top the pulp to be treated, in a substantially tangential direction, and a rotating continuous spiral blade for discharging the separated coarser material through the central discharge outlet, said spiral blade being so arranged that its lower edge is at a short distance above the conical bottom, and constructed so that the sides are substantially vertical, as set forth.

DONALD MACLEAN. 145
